UNITED STATES PATENT OFFICE.

CHARLES A. NACE, OF SANTA CLARA, CALIFORNIA.

AUTOMATIC PAPER-ADJUSTER AND GAGE-PIN FOR PLATEN PRINTING-PRESSES.

1,241,241.

Specification of Letters Patent. Patented Sept. 25, 1917.

Application filed September 11, 1916. Serial No. 119,463.

To all whom it may concern:

Be it known that I, CHARLES A. NACE, a citizen of the United States, residing at Santa Clara, in the county of Santa Clara and State of California, have invented new and useful Improvements in Automatic Paper-Adjusters and Gage-Pins for Platen Printing-Presses, of which the following is a specification.

10 This invention relates to an automatic paper adjuster and gage pin for platen printing presses.

One of the objects of the present invention is to provide a simple, substantial, automatically operated mechanism for adjusting the paper on a platen with relation to the gage pins and the bed of the press, after the paper has been delivered to the platen by the feeder or operator, (particularly where 20 a perfect register is desirable).

A further object of the invention is to provide a movable finger which is adapted to engage the sheet and move it into engagement with a pair of stationary gage pins, and furthermore to provide a movable gage pin for adjusting the sheet laterally of the platen before it is brought into engagement with the type, or bed of the press, as will hereinafter be more fully described.

30 Further objects will hereinafter appear.

The invention consists of the parts and the construction and combination of parts as hereinafter more fully described and claimed, having reference to the accompanying drawings in which:—

Figure 1 is a perspective view of a standard form of platen printing press showing the application of the invention.

Fig. 2 is a perspective view of the movable finger and gage pin together with the connected operating mechanism.

Fig. 3 is an enlarged cross section of the movable gage pin.

Fig. 4 is a plan view of the platen and the grippers showing the application of the invention.

Referring to the drawings in detail A indicates the main frame of a standard form of platen printing press, 2 the bed of the press where the type is mounted, 3 the feeding table, 4 the platen, 5 the depressible gripper bar, and 6 6^a the gripper arms.

The automatic paper adjusting mechanism forming the subject matter of the present application, generally shown in Figs. 2 55 and 4, is carried entirely by the gripper arm shown at 6^a. This mechanism is constructed and operated as follows:—

Secured on the gripper arm 6^a in any suitable manner or as here shown by means of set screws 7, is a bracket plate 8. Pivotally mounted as at 9 on one end of said plate is an arm 10, and slidably and adjustably secured on the outer end of said arm is an inwardly projecting finger 10^a on the outer 65 end of which is provided a rubber shoe 11. Secured on the opposite end of the bracket plate 8 as at 12 is a leaf spring 13, the free end of which is pivotally attached as at 14 to the arm 10 on one side of the 70 pivot 9, and secured on top of the spring 13 is a second spring 15, the function of which will hereinafter be described. Mounted adjacent the arm 10 is a stop lug 16 which limits the inward swinging movement of the arm 10 about the pivot 9, and connecting said arm with the plate 8 is a second spring 17 which cooperates with the spring 13 to hold the arm in the full line position shown in Figs. 2 and 4. Secured 80 upon the gripper arm 6^a in a manner similar to the bracket plate 8 previously described, is a second bracket plate 18. Extending out from the inner face of said plate is a pin 19, and slidably mounted on 85 said pin is a block 20 which will hereinafter be termed the movable gage or gage block. Pivotally mounted on the bracket plate 18 on the end opposite the movable gage 20 is an arm 21, and connecting said arm with 90 the gage is a link 22. Secured upon the bracket plate 18 as at 23 is a leaf spring similar to the spring 13 previously described. The other end of the spring is pivotally connected with the arm 21 as at 95 24, and secured to said spring as at 25 is a second spring similar to the one previously described and shown at 15. The several leaf springs here shown are adapted to be compressed in a manner hereinafter to be 100 described, and said compression is transmitted in either instance to move the gage 20 and the arm 10.

In actual operation when it is desired to

5 prepare the platen for a certain job, it is only necessary to cover the platen with a draw sheet in the usual manner and to insert the stationary gage pins such as indicated at 30, 31 and 32. The operator when 10 working, moves the paper sheet by sheet from the table 3 down upon the platen, and delivers each individual sheet at a point where it will approximately engage with the stationary pins 30, 31 and 32. The 15 rising and the swinging movement of the platen causes the gripper arms 6 and 6^a, together with the attached mechanism here shown, to swing down into engagement with the platen a moment previous to its engagement with the type or bed of the press.

20 By referring to Fig. 2 it will be seen that the leaf springs 13 and 15 are elevated, or assume a higher plane than the co-operating leaf springs carried by the bracket plate 18. This arrangement causes the springs 15 and 16 to contact with the furniture on the bed of the press a moment previous to the engagement of the second 25 set of co-operating leaf springs. The arm 10 is therefore swung about its pivot 9 to assume the dotted line position shown at 10^b. The rubber shoe 11 on the finger in this manner engages the sheet and pulls it 30 in the direction of arrow *a* into positive engagement with the stationary gage pins 30 and 31.

35 The second set of co-operating leaf springs carried by the bracket plate 18 will next engage with the furniture on the bed of the press, and therefore forces the movable gage 20 out or away from the gripper arm to the dotted line position indicated at 20^a, see Fig. 4. The sheet is in this manner moved laterally upon the platen a positive distance 40 away from the stationary gage pin 32, and as this movement is always positive and uniform it can readily be seen that each sheet delivered is automatically adjusted to assume a pre-determined position with relation to the stationary gage pins, and the type or the bed of the press. A perfect 45 register is in this manner always obtained without relying upon the skill or judgment 50 of the feeder. It furthermore relieves the feeder of the necessity of taking the same amount of care when delivering a sheet to the gage pins as is otherwise necessary. For instance the sheet delivered by the 55 feeder might assume the dotted line position indicated at 40. This would make no material difference as the movement to the rubber tipped finger 11 would pull the sheet down into engagement with the stationary gage pins 30 and 31 and the movement of the movable gage 20 would adjust the sheet laterally to assume the position desired.

60 It can therefore be seen that comparatively little care is required on the part of the feeder as each sheet delivered is automati-

65 cally adjusted regardless of the position assumed when first delivered. The importance of the automatic adjusting mechanism does not only reside in the fact that a perfect register is always obtained 70 regardless of the position of the sheet when first delivered to the platen, but also in view of the fact that waste is practically speaking entirely eliminated; and the speed of the feeder materially increased. 75

80 Another advantage besides a perfect register where one or more colors are to be printed, is that the disadvantage of creeping of the draw-sheet is entirely overcome, and the operator is at the same time relieved of any worry as the automatic paper adjusting mechanism positively insures a perfect register. A greater production and an appreciably better quality of work is in this manner obtained; the use of the throw-off 85 being practically eliminated.

90 The gripper arms together with the gripper bar 5 are depressed and lowered down into engagement with the platen after the platen has swung approximately midway of the arc of travel with relation to the bed of the press. The rubber tipped finger 10^a together with the movable gage 20 are in this manner brought down into engagement with the sheet previously delivered, and are thus in position to positively engage and adjust the same a moment previous to the time that the impression is made. The co-operating leaf springs may engage either with the furniture or the chase in which the type 100 is mounted, and as the co-operating leaf springs are flattened or compressed every time an impression is made, it is apparent that comparatively small space is required. It is therefore possible to attach the mechanism to practically speaking any form of platen press without changing or interfering with any of the moving parts. The tongues indicated at 50 may be secured on the adjustable gage 20 in any suitable manner and are only provided for the purpose of positively holding down the sheet while the gage 20 is moving laterally to adjust the sheet. 110

115 The materials and finish of the several parts of the device may otherwise be such as the experience and judgment of the manufacturer may dictate.

I wish it understood that various changes in form, proportions and minor details of construction may be resorted to within the scope of the appended claims, and that I do not wish to limit myself to the specific design or construction here shown.

Having thus described my invention, what 125 I claim and desire to secure by Letters Patent is:—

1. In a printing press, a sliding gage, a member pivoted at one end, a link pivotally connected to the gage and to the other end 130

of the pivoted member, and means operable by closing of the press to swing the pivoted member and thereby the link and gage.

2. In a printing press, sheet engaging means to effect adjustment of the sheet, means to actuate said first means including an arched spring, and a reversely arched spring connected at its center to the first arched spring and adapted to have its ends compressed by impact against the furniture of the press.

3. In a printing press, separate means formed so as to be carried by one of the gripper arms for automatically adjusting a sheet placed on the platen in diverse directions to assume a predetermined position before the impression is made.

4. In a printing press, means formed so as to be carried by one of the gripper arms for automatically adjusting a sheet placed on the platen to assume a predetermined position before the impression is made, said means comprising a movable gage and an independent swinging finger both engageable with the sheet.

5. In a printing press, means formed so as to be carried by one of the gripper arms for automatically adjusting a sheet placed on the platen to assume a predetermined position before the impression is made, said means comprising a movable gage and a finger both engageable with the sheet, and means connected with said gage and finger engageable with the bed of the press when the platen swings up to take the impression, said means when engaging with the bed, being adapted to transmit a swinging movement to the finger, and a reciprocating movement to the gage.

40 6. In a printing press, independent means to engage a sheet to adjust same laterally and longitudinally of the platen, and independent means associated with the respective first named means to separately actuate

45 the latter, said actuating means being formed of different degrees of projection so as to be operated by direct impact of the press furniture thereagainst and at intervals of time.

50 7. In a printing press, reciprocal means engageable with a sheet to adjust same in one direction on the platen, swinging means engageable with the sheet to adjust same in a second direction, and means to independently actuate each of the said means, said actuating means being formed of different degrees of projection so as to be operated by direct impact of the press furniture thereagainst and at intervals of time.

55 8. In a printing press, an adjustable bracket plate formed so as to be secured on one of the gripper arms, a pin extending from one side of the plate, a block slidably mounted on said pin, a lever pivotally mounted at one end on the plate, a link con-

nnecting the other end of said lever with the sliding block, and means actuated by the movement of the platen to swing the lever about the pivot.

9. In a printing press, an adjustable 70 bracket plate formed so as to be secured on one of the gripper arms, a pin extending from one side of the plate, a block slidably mounted on said pin, a lever pivotally mounted at one end on the plate, a link 75 connecting the other end of said lever with the sliding block, and a spring leaf secured at one end to the bracket plate and having its other end pivotally connected to the lever, said spring being positioned to engage the 80 bed of the press when the platen is raised to take the impression.

10. In a printing press, an adjustable bracket plate formed so as to be secured on one of the gripper arms, a pin extending 85 from one side of the plate, a block slidably mounted on said pin, a lever pivotally mounted at one end of the plate, a link connecting the other end of said lever with the sliding block, a lever pivotally mounted on 90 said plate, a rubber tipped finger on the other end of said lever, and means actuated by the movement of the platen to swing the lever about its pivot.

11. In a printing press, an adjustable 95 bracket plate secured on one of the gripper arms, a pin extending from one side of the plate, a block slidably mounted on said pin, a lever pivotally mounted at one end of the plate, a link connecting the other end of 100 said lever with the sliding block, a lever pivotally mounted on said plate, a rubber tipped finger on the other end of said lever, and a spring leaf secured at one end to the bracket plate and having its other end pivot- 105 ally connected to the lever, said spring being positioned to engage the bed of the press when the platen is raised to take the im- pression.

12. In a printing press, means operable 110 by direct impact thereagainst upon closing of the press to engage a sheet and adjust same in one direction, and other means operable by direct impact thereagainst upon closing of the press but at a period of time 115 subsequent to the operation of the first means for adjusting the sheet in a second direction.

13. In a printing press, sheet engaging means to adjust the paper, means pivoted to 120 mount said means for movement, and an arched extensible spring pivoted at one end and being in positive connection with the actuating means at its other end to actuate the latter upon extension of the spring by 125 and upon impact of the latter with the press furniture.

14. In a printing press, a pivoted swing- ing element having sheet engaging means connected thereto and extensible and con- 130

tractible means connected at one end to a relatively fixed point and pivotally connected at its other end to said element to one side of the pivot of the latter to effect movement of the element upon impact of said means with a relatively moving part of the press.

In testimony whereof I have hereunto set my hand in the presence of two subscribing witnesses.

CHARLES A. NACE.
